UNITED STATES PATENT OFFICE

2,404,365

PRODUCTION OF FAT-SOLUBLE VITAMIN
ESTER CONCENTRATES

Charles E. Dryden, East Orange, and Loran O. Buxton, Newark, N. J., assignors to National Oil Products Company, Harrison, N. J., a corporation of New Jersey

No Drawing. Application September 28, 1944,
Serial No. 556,284

10 Claims. (Cl. 167—81)

1 The present invention relates to the production of fat soluble vitamin concentrates from natural oils and fats containing the same. More particularly, the present invention relates to the production of relatively high potency vitamin A concentrates wherein the vitamin A is largely in natural ester form from materials of marine origin containing vitamins A and D.

Various methods of concentrating the vitamin content of oils of marine origin containing vitamins are known in the art, among them, processes which include saponification of the fatty acid glycerides by means of caustic soda or caustic potash. In general, prior art saponification processes contemplate complete saponification of all the saponifiable constituents of the oil in an effort to produce concentrates of vitamins of the highest potency. In a process of this character, the vitamin and other higher alcohol esters are converted to soaps, vitamin alcohols and other higher alcohols. Vitamin alcohols are separated from the residual soaps and other components of the oils. The concentrate thus produced is of a relatively high potency, but the vitamin is substantially completely in an alcohol form rather than in the natural ester form. Among the disadvantages of such a process is that the vitamin alcohol is much more subject to oxidation and upon storage for any length of time exhibits a lesser biological potency than the natural ester.

In U. S. application Serial No. 450,757, a process involving a partial saponification of fish liver oils and the like to produce vitamin concentrates wherein a substantial portion of the original vitamin content is obtained in ester form is disclosed. The process set forth in the aforementioned application includes the addition of sufficient alkali to partially saponify the saponifiable matter in the oil. Thereafter the soap formed is separated as by extracting the nonsaponified residue with ethylene dichloride and the resultant nonsaponified residue after removal of the ethylene dichloride is then further extracted with a polar solvent such as methanol to remove the vitamin A alcohol. The resultant ester concentrate produced is of considerably higher potency than the original oil. However, there are limits to the strength of the ester concentrate produced from any particular oil since a higher degree of saponification tends to hydrolyze a greater amount of the vitamin ester to the vitamin A alcohol. In practicing the process of the aforementioned application, therefore, the vitamin-containing oil is saponified to an extent which will produce the highest potency ester concentrate and still hy-

drolyze only a minor proportion of the vitamin A ester in the original oil to the vitamin alcohol. By proceeding in this manner, it is therefore possible to produce ester concentrates of considerably greater potency than the original oil while at the same time hydrolyzing only a small amount of the ester of the original oil.

Although it has been proposed in accordance with the aforementioned application to reduce the speed of reaction as by limiting the amount of catalyst or the concentration of the alkali and although the slower reaction thus effected has increased the potency of the vitamin A ester produced, it has not been possible when proceeding with the reaction under adiabatic conditions, as set forth in the prior application, to slow down the speed of reaction sufficiently to greatly increase the potency of the resultant vitamin ester concentrates by such means. Inasmuch as the reaction with the alkali is exothermic, the temperature of the mixture of alkali and the oil being treated normally rose to a temperature of approximately 50–60° during the reaction, and this was true no matter how slowly the caustic was added during saponification. In accordance with the teachings of the prior art, this was not undesirable, since some of the prior patents even taught the desirability of heating the mixture of caustic and oil in order to produce a more complete saponification.

2 In accordance with the present invention, however, it has now been discovered that if the reaction mixture of caustic and oil is cooled during the reaction so that it is maintained under isothermal conditions and preferably at temperatures below approximately 35° C., a much higher potency vitamin ester concentrate is produced and at the same time a lesser amount of vitamin A ester is hydrolyzed to vitamin A alcohol. The exact reason for this phenomenon is not clearly understood, but it is evident that that portion of the fatty acid glycerides which is not saponified during the incomplete saponification is rendered soluble in a polar solvent such as methanol, probably due to mono and diglyceride formation. Thus when the residue after separation of the soap is treated with a polar solvent such as methanol, a relatively large proportion of the nonsaponified nonvitamin content is removed to leave behind a more potent vitamin ester concentrate. Further, during the reaction a much lesser quantity of the vitamin ester is hydrolyzed to vitamin alcohol. It has therefore become possible to not only separate the vitamin ester in relatively large yields from the remaining com-

ponents of the oil, but also to concentrate the ester by means of a simple process so that vitamin ester concentrates of relatively high potency are produced. Further, higher yields are obtained considering both vitamin ester and alcohol as compared to the total amount of vitamin in the original oil.

It is one of the objects of the present invention, therefore, to prepare vitamin concentrates from natural vitamin containing materials by partial saponification, while cooling the oil so as to produce vitamin ester concentrates of relatively high potency.

A second object of the present invention is to provide an isothermal process for the partial saponification of fish liver oils and the like, whereby a much lesser proportion of vitamin ester is hydrolyzed to vitamin alcohol.

A third object of the present invention is to partially saponify a vitamin ester containing marine material while cooling the same so as to form as large a proportion as possible of polar solvent soluble material from the unsaponified non-vitamin components so that upon treatment with a polar solvent such as methanol a vitamin ester concentrate of a relatively high potency remains.

Other objects and advantages of the present invention will be apparent from the present description and claims.

In general, it is preferable when practicing the present process to add the caustic at a relatively slow rate. Thus a portion of the caustic may be added in relatively concentrated form over a substantial period, and the additional caustic added in relatively dilute form over another period; or, in the alternative, a relatively more dilute caustic may be slowly added. In general, the lower the temperature of reaction, the less the quantity of ester converted to alcohol form, and the temperature of reaction should be as low as possible depending on the temperature at which the oil tends to solidify and the reaction tends to slow up to such an extent that a complete reaction will not take place. In general, temperatures below about 35° C. are used and temperatures from 0° C. to 25° C. have been found to be particularly suitable. As may be understood, the temperature of the reacting mass may be kept at the desired range during saponification by any suitable cooling means.

The present process is applicable to the production of vitamin concentrates from various types of vitamin containing materials and particularly materials of marine origin containing vitamins A and D. Such oils are the fish liver oils such as cod liver oil, ling cod liver oil, pollack liver oil, tuna liver oil, shark liver oil, dogfish liver oil, mackerel liver oil, sword fish liver oil, spear fish liver oil, sole liver oil and halibut liver oil. Marine oils such as sardine oil, pilchard oil, herring oil, seal oil and whale oil are also suitable. In place of the oils which have been obtained from the raw material by cold pressing processes or other conventional means, solvent extracts and partial concentrates of oils of the character described may also be used as, for example, the isopropanol extracts of the liver and marine oils specified.

The partial selective saponification is carried out by treating a vitamin-containing material of the character set forth with caustic in the manner well known in the art for preparing vitamin concentrates, except that the amount of caustic used is always insufficient to completely saponify the oil. As pointed out in the aforementioned

75 prior application, under conditions of partial saponification, a substantial proportion of the vitamin esters remains intact, and the saturated glycerides are substantially completely saponified along with a portion of the unsaturated glycerides.

In general, when proceeding with the present process, i. e. the low temperature and isothermal saponification, a much lower percentage of vitamin alcohols is produced than when proceeding in accordance with the process of the prior application. A certain amount of vitamin alcohol, however, naturally occurs in the oil, and the unsaponified mass contains this small proportion of vitamin alcohol, a part of the unsaturated glycerides present in the original oil unsaponifiable matter, glycerine, soaps, etc.

The present process can be practiced, at least to some degree, with any degree of saponification of the oil up to approximately 98% saponification.

20 In general, the amount of the caustic employed will be that equivalent to somewhat less than 98% with the larger amounts of caustic increasing the potency of the vitamin alcohol portion extracted by means of methanol and correspondingly tending to hydrolyze a greater proportion of the vitamin ester to the alcohol. In general, sufficient caustic will be employed in the present process equivalent to the saponification of from 60 to about 95% of the saponifiable matter in the oil. 25 The saponification reaction may be retarded by other means in addition to the temperature control, for example, the oil may be diluted with a suitable inert solvent such as a nonpolar solvent on the order of ethylene dichloride, heptane, trichlorethylene, hexane, cyclohexane, methyl cyclohexane, or a mixture of inert solvents. If a solvent is employed, the weight of the solvent should range from about 15 to 99% and preferably from about 25-75% to obtain the most efficient selective saponification. Saponification may also be retarded by reducing the amount of catalyst ordinarily employed in the saponification reaction. Usually, in saponifications of this type, from about 2 to 5% of isopropanol or other polar catalyst is employed. This allows the saponification reaction to take place without high heating. However, from 1/2 to 1% of isopropanol or other catalyst has been found satisfactory, even at the low temperatures of the present process. The speed 30 of the reaction may also be retarded by utilizing less concentrated caustic.

It will be understood from the foregoing that the present reaction may be retarded in order to produce the greatest potency ester concentrates by the use of a solvent or diluent of an inert character, by use of a lower catalyst concentration and a lower caustic concentration. In general a caustic concentration equivalent to 30% to 50% of caustic soda or potash is suitable. All 35 of these factors, however, do not give rise to the desirable results of the present invention, unless the temperature is also maintained at a relatively low level, as before stated, below approximately 35° C.

60 After the saponification is complete, i. e. in from 1 to 12 hours, the semi-concentrate is extracted from the partially saponified mass by the use of a nonpolar solvent. The particular method for the extraction is described in detail in copending application Serial No. 533,256, wherein it is pointed out that the separation of the soap from the solvent should preferably take place at an elevated temperature as, for example, from 40-80° and preferably from 60-70° C. Further, during this separation which takes place rapidly

at this elevated temperature, the amount of water present should be regulated from 12-35% and, in some instances, as high as 50% as compared to the weight of the soap produced. Preferably, the amount of water should be determined by the solubility of the soap in the extraction solvent, preferably ethylene dichloride; the amount of water being regulated so that from $\frac{1}{2}$ to 5% of the soap and preferably somewhat less than 1% is soluble in the ethylene dichloride. The present low temperature saponification gives rise to vitamin ester concentrates of the highest potency when used in conjunction with the high temperature rapid extraction of the semi-concentrate from the soap produced in accordance with the just mentioned prior application.

It is to be noted that although in this prior application it is pointed out that it is desirable for the extracted vitamin semi-concentrate to remain in contact with alkali for the shortest period of time so that the biological potency of the concentrates produced may be enhanced, even though in the present process the low temperature saponification takes a considerable length of time as compared to relatively high temperature saponification, this does not have a deleterious effect on the concentrates produced. This is probably due to the low temperature involved. However, after the saponification reaction is complete and the mass of soap and saponified matter is heated, as by the addition of hot solvent for fractionation, it is desirable at these temperatures in the neighborhood of 50-80° C. that the separation of the soap from the solvent extract take place as rapidly as possible. The extraction may then be carried out a number of times with lesser quantities of ethylene dichloride or other suitable solvent as mentioned in the prior application, and the resultant concentrates combined. Thereafter, the ethylene dichloride is removed by any suitable means to produce a semi-concentrate. The semi-concentrates may then be fractionated by means of polar solvents or they may be fractionated by processes other than selective solvent extraction as, for example, high vacuum distillation, vacuum distillation, absorption, etc. It is preferred, however, that a fractionation with polar solvents be carried out and preferably the polar solvent used is methanol or ethanol. However, any other solvent which is characterized by being miscible with (a solvent for) vitamin alcohols but immiscible with (a nonsolvent for) vitamin esters, may be employed in lieu of or in conjunction with methanol or ethanol. Such solvents include, among others, isopropanol, n-butanol, acetone and diacetone alcohol, each of which has been modified by the addition of at least 9% water, methanol, and/or ethanol. As previously pointed out, a large proportion of the unsaponified material aside from the vitamin esters is rendered soluble in solvents of the character just described and consequently the extraction yields a concentrated vitamin ester residue.

Example I

100 grams of a soupfin shark liver oil containing 63,200 units of vitamin A per gram were placed in a beaker immersed in ice water maintained at a temperature of 4° C. with ice. 31.2 grams of 49% KOH, sufficient to saponify 82% of the glycerides in the oil, and 15 grams of water (sufficient to make the water content of the wet soap produced 25% on completion of the reaction) were stirred in. The reaction mixture was stirred for 2 hours and then allowed to settle for

about $\frac{3}{4}$ hour. The average temperature of the oil and soap mixture during mixing was about 13° C. The soap produced was extracted successively with 500 cc. of ethylene dichloride at 65° C., a total of six extractions being made. The combined extracts were kept at 0° C. overnight, filtered and the solvent removed under vacuum. The semi-concentrate thus produced had a potency of 331,000 units of vitamin A per gram. Thereafter the semi-concentrate was extracted three times with 5 volumes of methyl alcohol, the mixture of alcohol and semi-concentrate being first heated to 50° C. and then cooled to -18° C. and decanted. The vitamin content of the residue ester fraction was equivalent to 58% of the total vitamin A recovered. The potency of the ester fraction was 477,000 units of vitamin A per gram. The total overall vitamin A recovery, i. e. the vitamin A in the methanol extract as well as that in the residue was equal to 97.9% of the original vitamin A in the oil. A similar reaction to the above was carried out, except that the oil was not cooled during saponification. The temperature in this case rose to a maximum of 62° C. in 7 minutes. As compared to the reaction at low temperature, only 38.9% vitamin A was recovered in ester form. Although the semi-concentrate produced had a potency of 300,000 units of vitamin A per gram, the potency of the ester fraction i. e. the methyl extract residue of the semi-concentrate was only 172,000 units of vitamin A per gram. The overall yield of vitamin A from the high temperature process was 94.3%.

Example II

32.7% KOH was added while stirring to saponify 70% of the glycerides in the oil, i. e. 35.5 grams of 32.7% KOH. The mass was stirred for a period of one hour and was thereafter stored at 3° C. for 16 hours. The average temperature during saponification was 1° C. After storage, the soap was extracted five times with ethylene dichloride at 70° C. 500 cc. of ethylene dichloride were used for the first extraction and 300 cc. for successive extractions. The combined extracts were kept at 0° C. overnight, filtered and the ethylene dichloride removed under vacuum. The semi-concentrate thus produced was then extracted with methanol as in Examples I and II. The following results were obtained:

	Units of vitamin A per gram
Vitamin potency of semi-concentrate	605,000
Vitamin potency of alcohol (methanol extract)	256,000
Vitamin potency of ester (methanol residue)	680,000
Overall yield of vitamin A	98.6%.

Example IV

100 grams of halibut liver oil having a potency of 92,500 units of vitamin A per gram were placed in a beaker immersed in ice water maintained at a temperature of -8° C. with ice. 3% by weight of isopropanol was added and then sufficient 36.8% KOH was added while stirring to saponify 70% of the glycerides in the oil, i. e. 32.6% of 36.8% KOH. The total time of stirring was 1 hour, and the average temperature during saponification of the oil 0° C. Thereafter the mass was stored for 18 hours at 3° C. The soap was then extracted five times with ethylene dichloride at 70° C. 500 cc. of ethylene dichloride were used for the first extraction and 300 cc. for subsequent extractions. The combined extracts were kept at 0° C. overnight and filtered. The ethylene dichloride was then removed under vacuum. The semi-concentrate thus produced was then extracted with methanol as in the preceding examples. The following results were obtained:

	Units of vitamin A per gram
Vitamin potency of semi-concentrate	252,000
Vitamin potency of alcohol (methanol extract)	192,000
Vitamin potency of ester (methanol residue)	320,000
Overall yield of vitamin A	approximately 100%.

As will be noted from the above examples, in each case the potency of the ester concentrate produced was higher than that of the semi-concentrate. In other words, even with the removal of the vitamin A alcohol sufficient methanol soluble material was removed so that the potency of the residue was enhanced. As previously pointed out in the present specification, it is believed that this solubilization effect on the nonsaponified and nonvitamin material in the semi-concentrate is probably due to the formation of mono and di-glycerides during the low temperature saponification process of the present invention. However, it is not desired to be limited by this theory.

Having described our invention, what we claim as new and desire to be secured by Letters Patent is:

1. A process for the production of fat soluble vitamin ester concentrates from vitamin containing material of marine origin comprising partially saponifying while cooling the material so as to

render a relatively large proportion of the material other than the vitamin ester and soap formed soluble in a polar solvent, separating the soap from the unsaponified residue and treating the unsaponified residue with a highly polar selective solvent which is characterized by being miscible with fat-soluble vitamin alcohols but immiscible with fat soluble vitamin esters to remove that portion of the residue soluble therein and produce a concentrate high in vitamin ester content.

2. A process for the production of fat soluble vitamin ester concentrates from vitamin containing material of marine origin comprising partially saponifying said material while cooling the same to below approximately 35° C. so as to render a relatively large proportion of the material other than the vitamin ester and soap formed soluble in a polar solvent, separating the soap from the unsaponified residue and treating the unsaponified residue with a highly polar selective solvent which is characterized by being miscible with fat-soluble vitamin alcohols but immiscible with fat soluble vitamin esters to remove that portion of the residue soluble therein and produce a concentrate high in vitamin ester content.

3. A process for the production of fat soluble vitamin ester concentrates from vitamin containing material of marine origin comprising partially saponifying while cooling the material so as to render a relatively large proportion of the material other than the vitamin ester and soap formed soluble in methanol, separating the soap from the unsaponified residue and treating the unsaponified residue with methanol to remove that portion of the residue soluble therein and produce a concentrate high in vitamin ester content.

4. A process for the production of fat soluble vitamin ester concentrates from vitamin containing material of marine origin comprising partially saponifying said material while cooling the same to below approximately 35° C. so as to render a relatively large proportion of the material other than the vitamin ester and soap formed soluble in methanol, separating the soap from the unsaponified residue and treating the unsaponified residue with methanol to remove that portion of the residue soluble therein and produce a concentrate high in vitamin ester content.

5. A process for the production of fat soluble vitamin ester concentrates from vitamin containing material of marine origin comprising partially saponifying while cooling the material so as to render a relatively large proportion of the material other than the vitamin ester and soap formed soluble in ethanol, separating the soap from the unsaponified residue and treating the unsaponified residue with ethanol to remove that portion of the residue soluble therein and produce a concentrate high in vitamin ester content.

6. A process for the production of fat soluble vitamin ester concentrates from vitamin containing material of marine origin comprising partially saponifying said material while cooling the same to below approximately 35° C. so as to render a relatively large proportion of the material other than the vitamin ester and soap formed soluble in ethanol, separating the soap from the unsaponified residue and treating the unsaponified residue with ethanol to remove that portion of the residue soluble therein and produce a concentrate high in vitamin ester content.

7. A process for the production of fat soluble vitamin ester concentrates from fish liver oils

which comprises partially saponifying a fish liver oil while cooling the same to maintain the temperature substantially constant during saponification so as to render a relatively large proportion of the material other than the vitamin ester and soap formed soluble in a polar solvent, separating the soap from the unsaponified residue and treating the unsaponified residue with a highly polar selective solvent which is characterized by being miscible with fat-soluble vitamin alcohols but immiscible with fat soluble vitamin esters to remove that portion of the residue soluble therein and produce a concentrate high in vitamin ester content.

8. A process for the production of fat soluble vitamin ester concentrates from vitamin containing material of marine origin comprising partially saponifying the said material while maintaining the temperature thereof during saponification between approximately 0-25° C., separating the soap from the unsaponified residue and treating the unsaponified residue with a highly polar selective solvent which is characterized by being miscible with fat-soluble vitamin alcohols but immiscible with fat soluble vitamin esters to remove that portion of the residue soluble therein

15

and produce a concentrate high in vitamin ester content.

9. A process for the production of fat soluble vitamin ester concentrates from vitamin containing material of marine origin comprising partially saponifying the said material while maintaining the temperature thereof during saponification between approximately 0-25° C., separating the soap from the unsaponified residue and treating the unsaponified residue with methanol to remove that portion of the residue soluble therein and produce a concentrate high in vitamin ester content.

10. A process for the production of fat soluble vitamin ester concentrates from vitamin containing material of marine origin comprising partially saponifying the said material while maintaining the temperature thereof during saponification between approximately 0-25° C., separating the soap from the unsaponified residue and treating the unsaponified residue with ethanol to remove that portion of the residue soluble therein and produce a concentrate high in vitamin ester content.
